UNITED STATES PATENT OFFICE.

MICHAEL LIPTAK, OF ST. PAUL, MINNESOTA, ASSIGNOR TO A. P. GREEN FIRE BRICK COMPANY, OF MEXICO, MISSOURI, A CORPORATION OF MISSOURI.

FURNACE WALL.

Application filed December 10, 1921. Serial No. 521,376.

To all whom it may concern:

Be it known that I, MICHAEL LIPTAK, a citizen of the United States, residing at St. Paul, in the county of Ramsey and State 5 of Minnesota, have invented certain new and useful Improvements in Furnace Walls; and I do hereby declare the following to be a full, clear, and exact description of the invention, such as will enable others skilled 10 in the art to which it appertains to make and use the same.

My present invention has for its object to improve the construction of furnace walls with a view of providing a simple, inexpensive and commercially practicable means for 15 quick replacement of the inner or high temperature brick or tile inner wall facing without materially defacing the outer masonry wall. Generally stated, the invention 20 consists of the novel construction, arrangement and combinations of parts hereinafter described and defined in the claims.

In a general way, this invention is in the nature of a modification of or improvement 25 on the form of furnace wall illustrated in the drawings of my pending application Serial Number 408,699, filed September 7, 1920, and broadly claimed in said prior application.

In the wall of the present application, the outer masonry wall is or may be made up entirely of masonry blocks, towit: bricks or tiles, and the replaceable inner lining of the 30 wall is made up entirely of high temperature blocks, towit: fire bricks or tiles. As a distinctive feature of the present invention, the inner high temperature wall comprises horizontally aligned but horizontally 35 spaced shelf-forming tiles that are extended into and partly imbedded within the outer masonry wall. These shelf-forming tiles, thus supported from the outer masonry wall, together with supplemental shelf-forming tiles interposed between and supported thereby but not extended into the outer masonry wall, form vertically spaced horizontally extended shelves upon which the fire bricks of the high temperature inner or replaceable wall are laid to form vertically spaced horizontally extending replaceable wall sections. The important results 45 accomplished by the arrangement above generally indicated will be more fully considered after first having described the

preferred embodiment of the present invention. 55

In the accompanying drawings, which illustrate the invention, like characters indicate like parts throughout the several views. 60

Referring to the drawings:

Fig. 1 is a fragmentary perspective with some parts removed, showing a furnace wall designed in accordance with my invention; 65

Fig. 2 is a perspective showing one of the anchored shelf-supporting tiles; 70

Fig. 3 is a perspective showing one of the supplemental shelf-forming tiles;

Fig. 4 is a perspective showing one of the main tiles of the outer wall; 75

Fig. 5 is a perspective showing one of the supplemental tiles of the outer wall;

Fig. 6 is a fragmentary plan view of the wall shown in Fig. 1, some of the tiles of the outer wall and shelf-forming tiles of the inner wall being removed; 80

Fig. 7 is a fragmentary elevation looking at the inner or high temperature face of the wall;

Fig. 8 is a vertical section taken approximately on the line 8—8 of Fig. 7; 85

Fig. 9 is a fragmentary elevation looking at the outer face of the wall;

Fig. 10 is a plan view of the wall structure shown in Figs. 1 to 9, inclusive, but showing the main shelf-forming tiles and the supplemental shelf-forming tiles all removed; 90

Fig. 11 is a fragmentary elevation looking at the inner surface of the outer wall, the inner or replaceable inner wall, including the supplemental and main shelf-forming tiles, being removed; 95

Fig. 12 is a view corresponding to Fig. 1, but illustrating a slightly modified construction;

Fig. 13 is a perspective showing certain of the blocks of the shelf-forming course removed from the wall and slightly separated from each other; 100

Fig. 14 is a plan view of the wall shown in Fig. 10; and

Fig. 15 is a fragmentary elevation looking at the inner surface of the outer wall, the inner or replaceable wall, including the main shelf-forming tiles, being removed. 105

The outer or permanent masonry wall is made up chiefly of ordinary bricks 10 laid

in mortar in the customary way, but to provide for the shelves to support the horizontal sections of the replaceable inner or fire wall proper, said outer masonry wall is 5 provided, on certain horizontal lines, with tile courses made up preferably of fire tiles 11, 12 and 13. The tiles 12 are the full width of the masonry wall 10. The tiles 11 are the main shelf-forming and supporting 10 tiles of the replaceable inner wall and they are partly imbedded in the outer masonry wall 10 but project so that they will be flush with the inner surface of the replaceable inner wall. The tiles 13 are located between 15 the tiles 12, aligned with the imbedded ends of the tiles 11 so that the said tiles 11, 12 and 13, when assembled, form a complete layer in the outer wall, with the tiles 11, as indicated, projecting for the purpose 20 stated.

To adapt the anchored shelf tiles 11 to support the supplemental shelf tiles 14, said tiles 11, at their parallel edges, are rabbeted at 15 and the edges of the supplemental 25 tiles 14 are reversely rabbeted so that the latter will be supported by and horizontally flush with the former.

The main body portion of the replaceable inner wall is made up of high temperature or fire bricks 16 laid in superimposed horizontal courses on the shelf-forming tiles, filling in the spaces between the vertically spaced horizontal shelves, as best shown in Fig. 1.

From the above, it is evident that the complete furnace wall, including what is herein particularly designated as the permanent outer masonry wall and the replaceable inner fire wall, may be made up entirely of masonry work.

When any portion of the inner fire wall has been burned away to a point where it requires replacement, the defective fire bricks or tiles may be removed and replaced 45 without disturbing or taking down the permanent outer wall. If only a few of the bricks 16 have been burned away, they may be removed and replaced without disturbing the shelf tiles. However, usually also 50 some of the shelf tiles will be burned and require replacement and this may be done as follows: Obviously, the replacement of one of the supplemental shelf tiles 14 is a very simple matter since it does not extend 55 into the outer wall. If one of the partly imbedded main shelf tiles 11 requires replacement, it may be easily pulled or knocked out of position, thereby making possible the replacement thereof by a new 60 tile of the same character. This may be very readily done. Moreover, it may be done without appreciably weakening the outer wall. This is so even if all of the said tiles 11 should be removed at one time, because 65 the inner portion of said outer wall,

between the horizontally spaced tiles 11, is left entirely intact, thereby affording the best kind of a support for the entire wall. Hence, it will be appreciated that it is important that said tiles 11 be spaced horizontally 70 as described and that the shelves be completed by the supplemental tiles 14 that do not extend into the outer wall. However, in practice, only a few of the tiles 11 will necessarily be removed at any one 75 time.

From what has been said, it, of course, follows that the inner wall sections between the supporting shelves may be independently repaired, in whole or in part, without disturbing other sections. However, it will 80 seldom be necessary to replace any complete horizontal wall section at any one time, but the repairs will usually be local or at different spots or places. With such an arrangement, the outer wall structure will last indefinitely, while the inner fire wall may be replaced as often as required. This, of course, reduces the cost of repairs and maintenance of the complete furnace to 90 a minimum and also makes it possible to quickly make such repairs with a resulting minimum loss of time in the use of the furnace, which is, in itself, frequently more important than the direct cost of the repairs. 95

By reference particularly to Figs. 10 and 11, it will be noted that even when the inner replaceable wall, including both the main and supplemental shelf-forming tiles, are 100 removed, the outer or permanent wall is not materially weakened but is simply formed with a plurality of pockets or depressions and between such pockets and depressions is left intact or, in other words, formed with 105 complete pilasters that are the full width of the outer wall and the pockets are rigidly bridged between these pilasters.

The somewhat modified construction illustrated in Figs. 12, 13, 14 and 15 is like that 110 illustrated in the views above described except that the main shelf-forming tiles 11^a are made wider than the tiles 11 and are centrally split or divided and the permanent wall tiles 13^a are made longer than the tiles 115 13 to fill the space back of each divided main shelf-forming tile 11^a. This arrangement increases the load-carrying capacity of the main shelf-supporting tiles and still does not appreciably weaken the permanent 120 outer wall even when all of the shelf-forming tiles are removed because the pilasters or complete wall structures are left intact between the pockets formed in the outer wall for said main shelf-supporting tiles. 125

It will, of course, be understood that the outer permanent wall, instead of being made entirely of commercial bricks, might be made in whole or in part of fire bricks. For instance, the inner bricks of the said 130

permanent outer wall might be fire bricks and the other bricks thereof might be commercial bricks.

What I claim is:

5. 1. A wall structure comprising a permanent masonry wall and a replaceable wall, said permanent wall having non-metallic elements constructed and arranged to form horizontal rows of vertically spaced pockets, 10 and said replaceable wall including shelf-forming tiles that are detachably anchored in the pockets of said permanent wall and project into the replaceable wall and form horizontal shelves that support independently replaceable overlying belts of the latter.
2. A wall structure comprising a permanent masonry outer wall and a replaceable masonry inner wall, said inner wall including 20 main shelf-forming tiles partly imbedded directly in the masonry of said outer wall and horizontally spaced, and supplemental shelf-forming tiles supported by said main shelf-forming tiles and extended 25 only within the inner wall space, said shelf-forming tiles supporting the horizontal sections of said inner wall.
3. The structure defined in claim 2 in further combination with tiles in the outer wall 30 of the same thickness as said main shelf-forming tiles and, together with the imbedded portions of the latter, forming complete courses in said outer wall.
4. The structure defined in claim 2 in 35 which the masonry of said outer wall in a

vertical direction is complete and permanent between the imbedded portions of said main shelf-forming tiles.

5. The structure defined in claim 2 in which said main and supplemental shelf-forming tiles have overlapping rabbeted edges. 40

6. A wall structure comprising a permanent outer wall having laterally spaced vertical rows of pockets but formed complete 45 between said pockets, in combination with a replaceable inner wall including shelf-forming tiles having their outer portions anchored in the pockets of said outer wall.

7. The construction defined in claim 6 in 50 which said inner wall comprises masonry sections including said shelf-forming tiles.

8. The structure defined in claim 6 in which said replaceable inner wall includes supplemental shelf-forming tiles supported 55 on said anchored shelf-forming tiles, and includes also masonry sections made between said shelf-forming tiles.

9. The structure defined in claim 2 in which said main shelf-forming tiles are longitudinally split or divided, the sections thereof being laid edge to edge and imbedded in the same pockets of the outer wall. 60

10. The structure defined in claim 6 in 65 which said shelf-forming tiles are longitudinally split or divided and laid edge to edge.

In testimony whereof I affix my signature.
MICHAEL LIPTAK.
